UNITED STATES PATENT OFFICE.

WALTER N. HASKELL, OF STERLING, ILLINOIS.

SUITCASE.

1,367,043.

Specification of Letters Patent.

Patented Feb. 1, 1921.

Application filed September 14, 1916, Serial No. 120,066. Renewed June 25, 1920. Serial No. 391,836.

To all whom it may concern:

Be it known that I, WALTER N. HASKELL, a citizen of the United States, residing at Sterling, in the county of Whiteside and 5 State of Illinois, have invented certain new and useful Improvements in Suitcases, of which the following is a specification.

My invention pertains to suit-cases and similar articles, and has for its purpose to 10 provide a means whereby such devices and their contents will be safeguarded against theft, or against being carried away by mistake.

Travelers upon railway trains frequently 15 leave their suit-cases or traveling-bags unprotected while they spend some time in the smoking-car, dining-car, or toilet room. These articles are also left temporarily unguarded in railway stations, restaurants, 20 automobiles, and many other places. By the use of the present invention attention is at once attracted to the suit case upon an attempt being made by any person to appropriate the same wrongfully or by mistake.

25 In the drawings Figure 1 is a vertical longitudinal section of a portion of a suitcase, and my invention as applied thereto, with the parts locked. Fig. 2 is a similar view with the handle mechanism unlocked 30 and open. Fig. 3 shows a suit-case in side elevation, in position when attempted to be carried with the parts disconnected.

1 represents a suit-case of an ordinary pattern, of which only an upper fragmentary 35 part is illustrated in the first two figures, wherein the numeral 2 indicates the top of the main part of the suit-case. Fixed to the outer face of the top 2 is a casing 3, in one end of which is pivoted one end of a 40 handle 4, as at *a*, the opposite end of such handle being provided with an extension 5 adapted to pass through an opening 6 in the casing 3. The extension 5 is provided with an opening to admit the end of a bolt 7, 45 slidable in the casing 3. In the upper face of the bolt 7 is secured a thumb button 8, the shank of which is movable in a slot 9 in the casing 3. By this means the bolt can be withdrawn to release the extension 5.

50 In the lower face of the bolt 7 is a recess 10, adapted to be engaged by a pin 11, passing upwardly through an opening 12 in the top 2 and provided with an upward tension by means of a spring 13 secured at one end 55 on the inside of the top 2. The pin 11 is provided on its lower end with a knob 14,

by means of which it may be drawn downwardly to release the bolt. It will be evident that by the means just described it will be possible to operate the bolt 7 and release 60 the movable end of the handle 4, from the outside of the suit-case, but that the parts cannot be again connected except by opening the receptacle. The owner of the suit-case, upon depositing the same in a position 65 where it is to remain for a time, slides the bolt 7 inwardly, whereupon an attempt to lift the case by means of the handle will result in one end of the suit-case tipping downwardly as shown in Fig. 3. This will 70 at once attract the attention of other persons in the vicinity of the suit-case. When the owner wishes to again transport the case or bag, he opens the same, releases the bolt, and reconnects the handle.

75

Accidental slipping of the bolt 7 is prevented by means of a stop 15 fixed to the inner face of the casing 3, at the end of the bolt. The upward pressure of the pin 11 against the bolt 7 holds the end thereof in 80 contact with the stop, and prevents movement of said bolt inwardly, but when it is desired to operate the bolt, a slight downward pressure upon the button 8 will overcome the force of the spring 13, and permit 85 the bolt to pass beneath the stop.

The central portion of the casing 3 may be utilized for the usual locking devices of the suit-case, and while the locking mechanism for the handle 4 is entirely independent of 90 the means for locking the cover of the suit case, yet the two mechanisms can be easily connected mechanically, so that the turning of a key in the suit-case lock will operate to withdraw the pin 11, and permit the bolt 95 7 to be returned to a locking position without opening the suit-case.

While the devices hereinbefore shown and explained are amply sufficient to protect a suit-case in which they are incorporated, 100 from theft or accidental removal, additional security may be attained by the following means;—On the inside of the top 2 is secured a casing 16, containing an alarm mechanism, which, in the present embodiment, consists of a bell 17, capable of being sounded by a hammer 18, actuated by spring mechanism as at 19. The hammer 18 is normally held from movement by a pin 20, slidable in the casing 16, and connected at 105 its outer end with a projection 21 of the pivoted end of the handle 4, which projec-

105

110

tion is capable of movement in an opening 22 in the top 2. When the handle 4 is rocked on its pivot, as shown in Fig. 2, the pin 20 is drawn away from the hammer 18, 5 resulting in the ringing of the bell. This furnishes an additional means for attracting attention to the suit-case and conveying the information that the same is being attempted to be carried by someone other than 10 the owner thereof. Various alarm devices might be substituted for the one above set forth.

It is also obvious that numerous changes 15 can be made in the handle mechanism first set forth herein, without departing from the spirit of the invention.

While my invention has been shown and described herein as applied to a suit case, the same can be readily adapted for use with 20 traveling bags and other receptacles which are designed to be transported from one place to another by the owner thereof.

What I claim as my invention, and desire to secure by Letters Patent of the 25 United States, is;

1. A device of the class described, comprising a receptacle; a handle hingedly connected therewith at one of its ends, and provided at its opposite end with bolt engaging means; a bolt carried by said receptacle adapted to engage the free end of 30 said handle, operable from the outside of the receptacle; and a spring-controlled catch on the inside of said receptacle, adapted to hold said bolt in withdrawn position.

2. A device of the class described, comprising a receptacle; a handle hingedly con-

nected therewith at one of its ends, and provided at said hinged end with a tongue projecting into the receptacle; means for detachably holding the opposite end of said handle; and sounding devices within said receptacle operatively connected with said tongue.

3. A device of the class described, comprising a receptacle; a handle hingedly connected therewith at one of its ends, and provided at said hinged end with a tongue projecting into said receptacle; a bolt carried by said receptacle adapted to engage 40 the free end of said handle, operable from the outside of the receptacle; a spring-controlled catch on the inside of said receptacle, adapted to hold said bolt in withdrawn position; and sounding devices on the inside 45 of said receptacle operatively connected with said tongue.

4. A device of the class described, comprising a receptacle; a handle hingedly connected therewith at one of its ends, so as to 50 move in a vertical plane; means carried by said receptacle for detachable connection of the opposite end of said handle; and sounding devices operatively connected with the hinged end of said handle, so as to be operated upon the movement of the free end 55 of said handle away from the receptacle.

In testimony whereof I affix my signature in the presence of two witnesses.

WALTER N. HASKELL.
